UNITED STATES PATENT OFFICE.

FLORA M. OTIS, OF ANN ARBOR, MICHIGAN.

ELASTIC BED-PAN.

959,379.

Specification of Letters Patent. Patented May 24, 1910.

Application filed August 6, 1909. Serial No. 511,639.

To all whom it may concern:

Be it known that I, FLORA M. OTIS, a citizen of the United States, residing at Ann Arbor, in the county of Washtenaw and 5 State of Michigan, have invented new and useful Improvements in Elastic Bed-Pans, of which the following is a specification.

This invention relates to elastic bed pans, and has for an object to provide a bed pan 10 that will be particularly adapted to be used when the patient is receiving vaginal douches, and to provide a pan which, when in use, will present such elasticity as will obviate any discomfort on part of the patient.

15 A still further object of the invention is to provide a bed pan which will be composed of detachable parts, one part serving the purpose of the pan proper while the other part serves as a reservoir and is in direct communication with the first part.

Another object of the invention is to provide a pan that will be constructed of such material that will permit it to be used upon 20 an unconscious patient, obviating the use of rubber sheets or the like which are employed for the purpose of preventing soiling of the bed clothing.

The above mentioned and other objects are attained by the construction, combinations and arrangements of parts, as disclosed 30 on the drawing, set forth in this specification, and particularly pointed out in the appended claims.

In the drawing, forming a portion of this 35 specification and in which like numerals of reference indicate similar parts in the several views:—Figure 1 is a perspective view of the bed pan. Fig. 2 is a detail longitudinal section taken on the line 2—2 of 40 Fig. 1.

My improved bed pan is formed from rubber or similar elastic or flexible material which is adapted to present a very broad cushioning area, and as illustrated, the pan 45 comprises a main web or body portion 1 which is provided with inflated or other equivalent cushioning rim 2. The rim 2 is hollow as shown in Fig. 2 of the drawing and is provided with a detachable inflating tube 3. The tube 3 may be of any well known form but is preferably provided with a suitable mouth piece 4 at one end whereby 50 the rim may be conveniently inflated by the nurse or other attendant of a patient.

55 The main body or web portion of the pan is provided with an elongated radial neck 5

whose end adjacent to the main body or web portion 1 of the pan is enlarged, and as shown, the neck is formed with a guard portion 6 which is disposed in parallel spaced relation to the main body or web portion to form therewith a discharge mouth. The portion 6 is reinforced preferably by one or more plies of rubber or the like 7, the purpose of the said reinforcement being to present the desired or required rigidity at that point of the pan where it is essential to hold the portion 6 in its proper spaced relation to the main body or web portion. The outer extremity of the neck 5 carries a threaded nipple 8 which is adapted to be engaged by a threaded nipple 9 upon one end of an elastic reservoir 10. The reservoir 10 is located preferably in a plane with the neck 5 so as to form therewith a direct communication with the main body or web portion of the pan thus enabling waste matter to be effectively discharged from the pan and conveyed to the reservoir.

The construction just described is such 80 that the reservoir can be detached from the neck 5 whereby it can be used should it be so desired as an ice or hot water bag. By providing the nipple 9 it will be readily apparent that when the reservoir is detached 85 and it is desired to use the same as an ice or water bag the nipple is adapted to receive any well known form of plug or stopper. At the closed end the reservoir is provided with a suspension eye member or equivalent 90 device 11.

Upon reference particularly to Fig. 1 of the drawing it will be seen that the inflated rim portion of the body 1 is of a greater diameter at its center than at the end portion. This construction is such that the rim 95 will be effectively held against collapse and will readily sustain considerable weight of the patient.

I claim:—

1. A bed pan formed from elastic material and comprising a main body portion, a cushioning rim partly surrounding the said main body portion, a hollow neck extending from the main body portion, and a detachable 105 handle forming a reservoir removably engaged with the neck.

2. A bed pan formed from elastic material and provided with a main body portion having an inflatable rim, a neck extending 110 from the said main body portion, a guard carried by the neck and disposed in spaced

relation to the body, and a detachable handle forming a reservoir operatively connected with the neck and opening directly thereinto at one end, the opposite end of the reservoir being closed.

3. A bed pan formed from elastic material and comprising a main body portion, a cushioning rim upon the main body portion, an outwardly extending hollow neck upon the body portion, a guard upon the neck and extending partly across the body portion, reinforcing means extending transversely of the guard and supported at its ends upon portions of the rim, and a detachable handle forming a reservoir closed at its outer end and open at its inner end, the said inner end being detachably connected with the said neck.

4. A bed pan comprising a main body portion, a cushioning rim upon the main body portion, said rim having an enlarged central portion and reduced end portions, a hollow neck upon the main body portion and opening directly thereinto at one end, a handle forming a reservoir connected at one of its ends to the other end of the neck, and a guard extending from the neck and partly across the said main body portion of the pan.

In testimony whereof I affix my signature in presence of two witnesses.

FLORA M. OTIS.
